UNITED STATES PATENT OFFICE.

ROBERT DE POLO, OF CONNELLSVILLE, PENNSYLVANIA.

HEATING-SYSTEM ATTACHMENT FOR RANGES.

1,208,300.

Specification of Letters Patent. Patented Dec. 12, 1916.

Application filed June 30, 1916. Serial No. 106,849.

To all whom it may concern:

Be it known that I, ROBERT DE POLO, a citizen of the United States, residing at Connellsburg, in the county of Fayette, State of Pennsylvania, have invented a new and useful Heating-System Attachment for Ranges; and I do hereby declare the following to be a full, clear, and exact description of the invention, such as will enable others skilled in the art to which it appertains to make and use the same.

This invention relates to a new and useful heating system for use in connection with a cooking range or stove, whereby the heat, derived from the range or stove, may pass through the various flues of the system, for heating purposes at various places remote from the range.

One of the objects of the invention is to provide means whereby the various flues of the system may be cleaned.

In practical fields, the details of construction may necessitate alterations, falling within the scope of what is claimed.

The invention comprises further features and combination of parts, as hereinafter set forth, shown in the drawings and claimed.

In the drawings: Figure 1 is a view in front elevation and partly in section of a portion of the heating system that is adjacent the range or stove. Fig. 2 is a plan view showing parts in section. Fig. 3 is a vertical sectional view on line 3—3 of Fig. 2. Fig. 4 is a sectional view on line 4—4 of Fig. 1, showing the range or stove in plan view, showing the floor of the tank broken away to illustrate the flues therebeneath. Fig. 5 is a sectional view on line 5—5 of Fig. 1. Fig. 6 is a sectional view on line 6—6 of Fig. 4. Fig. 7 is a sectional view on line 7—7 of Fig. 5. Fig. 8 is a diagrammatic view showing the course the heat takes in passing through the system to a room or the like to be heated.

Referring more especially to the drawings, 1 designates a conventional form of range or cooking stove having a fire box 2 with the usual form of grate 3 therein, and provided with an oven 4. In the present invention, a suitable casing 5 is constructed of any suitable material, with or adjacent to the casing of the range or stove. The extreme lower back portion of the casing 5 is provided with three compartments 6, 7, and 8, and above the compartments 6, 7, and 8 are the flues 9, 10, 11, 12, 13, and 14. Inter-

mediate the extreme back portion of the casing 5 (where said compartments 6, 7, and 8, and said flues 9, 10, 11, 12, 13 and 14 are constructed) and the range or stove is a series of flues 15, 16, and 17. Extending through the wall of one side of the extreme back portion of the casing 5 is a pipe or conduit 18, which makes a turn or bend at 19 in the compartment 7, and extends through the wall 20 of the range or stove, and into the ash-pit 21, and terminates under the grate 3, thereby constituting means to carry cold air to and under the grate. The pipe or conduit 18 may be provided with a damper for controlling the cold air.

Arranged in the flue or passage 15 is a damper 22, which may be thrown to open or closed positions by means of a rod 23 and hand member 24. When the damper 22 is open as shown in Fig. 6 clearly, the smoke and the like passes directly through the upper part or portion 15a of the flue 15, and passes out through the chimney to the exterior atmosphere. However, should the damper 22 be closed, as shown in Fig. 7 clearly, the products of combustion pass through the opening 25, and through the opening 26 of the wall 27 of the casing 5, and upwardly through the flue 14, as indicated by the arrows 28 in Fig. 7. Said products of combustion after passing up through the flue 14 passes through the opening 29 at the upper part of the wall 30 and down through the flue 9, as indicated by the full line arrows 31. The products of combustion, as indicated by the full line arrows 31, pass through the opening 32 at the lower edge of the partition or wall 33, and then upwardly through the flue 10, through the opening 34 at the upper edge of the wall or partition 35, and then downwardly through the flue 11, through the opening 36 at the lower edge of the wall or partition 37, and upwardly through the flue 12, as indicated by the dotted line arrows 38 in Fig. 3. The products of combustion pass from the flue 12 through the opening 39 at the upper edge of the wall or partition 40, and then downwardly through the flue 13, into the compartment or chamber 16, and if the damper 41 (which is mounted in the upper part of the chamber or compartment 16) is open, the products of combustion pass through the passage 42, into the upper portion 15a or flue (which rises from the chamber or compartment 15) and passes out through the

110

chimney to the exterior atmosphere. By means of this passage of the products of combustion, the water in the chamber or compartment 43 is thoroughly heated, and 5 may be carried off by means of the pipe 44 to any suitable service location for use. The pipe 44 is provided with a valve for controlling the flow of heated water to the service location.

10 Arranged upon and forming a part of the upper plate of the range or stove is an auxiliary casing 46 forming a warming or heating chamber 47, there being an opening 48 in the top wall or oven plate 49, to carry the 15 heat from the oven into the warming chamber, in which articles of food that have been cooked on the range or stove may be placed, to be kept warm until used. The heat from the warming chamber 47 passes through the 20 opening 50 into the passage or flue 51, and should the damper 52 be open, the heat from said warming chamber will pass out through the flue 51 to the atmosphere, but should the damper 52 be closed, as indicated at *a* in 25 Fig. 1, the heat from said warming chamber will pass out through the pipe or conduit 53, and exit through a grate opening 54 into a room 55, as indicated in dotted lines in Fig. 8. The foul air in the room 55 is designed 30 to pass through the grate opening 56 down through the pipe or conduit 57, and into the compartment 17 of the casing 5, and then upwardly through the passage 58 through the flue 59, and out through the chimney to 35 the exterior atmosphere. A pipe or conduit 60 is provided with a valve 61, and leads or communicates with the water chamber 43, for supplying water therein. Extending downwardly through the chambers or compartments 6, 7, and 8, and having their upper ends communicating with the lower portions of the flues 10, 11, and 12 are pipes or conduits 62, through which suitable means

or tool may be inserted for cleaning out the flues. The pipes 62 are provided with covers 45 or caps 63. The casing 46 is provided with hinged closures 64, whereby access may be had to the interior of the warming chamber. The damper 41 is controlled by the rod 65 and hand member 66. 50

The invention having been set forth, what is claimed as new and useful is:—

In a heating system of the kind set forth, the combination of a range or stove and a casing constructed to the rear and as a part 55 of said range, of a water chamber in the upper part of the extreme back portion of said casing, said casing having a chamber at its lower part in communication with the fire pot of the range, said casing having a 60 flue extending direct from said chamber to and in communication with the atmosphere, said casing having a second flue in communication with said chamber merging into an upwardly and downwardly zigzag flue 65 having several bends under the water chamber, and terminating in a chamber in the lower part of said casing, said chamber in the lower part of said casing having a port 70 of communication with the first flue, said first flue where it merges from its chamber having a damper, to be opened or closed, whereby the heat may either pass through the first flue or the second and zigzag flues, said last named chamber where it has a port 75 of communication with the first flue having a damper, to be opened when the first damper is closed and vice versa.

In testimony whereof I have signed my name to this specification in the presence of 80 two subscribing witnesses.

ROBERT DE POLO.
